CLAIM

The ornamental design for a sous vide cooker, as shown and described.

DESCRIPTION

FIG. 1 is a first perspective view of the sous vide cooker; FIG. 2 is a second perspective view of the sous vide cooker; FIG. 3 is a front view of the sous vide cooker; FIG. 4 is a rear view of the sous vide cooker; FIG. 5 is a left side view of the sous vide cooker; FIG. 6 is a right side view of the sous vide cooker; FIG. 7 is a top view of the sous vide cooker; FIG. 8 is a bottom view of the sous vide cooker; FIG. 9 is a partially enlarged view of part I as shown in FIG. 1; FIG. 10 is a partially enlarged view of part II as shown in FIG. 2; FIG. 11 is a partially enlarged view of part III as shown in FIG. 3; and, FIG. 12 is a partially enlarged view of part IV as shown in FIG. 8.

The ornamental design which is claimed is shown in solid lines in the drawings. The broken lines in the drawings depict portions of the sous vide cooker that form no part of the claimed design.
